REVOLVABLE ARTICLE SUPPORT

Ira Bruce Young, Jr., Chattanooga, Tenn., assignor to
Stainless Metal Products, Inc., Chattanooga, Tenn., a
corporation of Tennessee

Filed Nov. 13, 1957, Ser. No. 696,149

3 Claims. (Cl. 211—131)

This invention relates generally to the class of supports and is directed particularly to a new revolvable support or display stand.

A particular object of the present invention is to provide a stand for the support and display of various types of small articles wherein there are provided for supporting such articles a multiplicity of vertically spaced trays, shelves or pans of unique design and wherein also the stand is formed in a novel manner to permit such revolvable trays or the like to be readily disposed at different elevations in accordance with the size of the articles placed thereon.

Another object of the invention is to provide an article support and display stand embodying a central standard having rotatably mounted thereon trays of a novel design or construction whereby the same have exceptional strength with extreme lightness of weight.

Still another object of the invention is to provide a revolvable article support and display stand embodying a base, a standard supported thereon or attached thereto and a number of individual and readily interchangeable trays supported on the standard for rotation thereabout, wherein the parts are so associated that the stand may be easily knocked down for packing or shipping.

Still another object of the invention is to provide an article support and display stand of the character stated which is designed for economical construction and which is also strong and durable and capable of supporting a multiplicity of heavy objects in such a manner that access may be had to any one thereof by reason of the rotatable mounting of the trays.

The invention will be best understood from a consideration of the following detail description taken in connection with the accompanying drawings forming part of the specification, with the understanding, however, that the invention is not confined to a strict conformity with the showing of the drawing but may be changed or modified so long as such changes or modifications mark no material departure from the salient features of the invention as expressed in the appended claims.

In the drawings:

Fig. 1 is a view in side elevation of an article support and display stand having revolvable trays or shelves, constructed in accordance with the preferred embodiment of the present invention;

Fig. 2 is a horizontal section taken substantially on the line 2—2 of Fig. 1;

Fig. 3 is a horizontal section taken substantially on the line 3—3 of Fig. 1;

Fig. 4 is a vertical section taken substantially on the line 4—4 of Fig. 1;

Fig. 5 is a vertical section taken substantially on the line 5—5 of Fig. 1;

Fig. 6 is a vertical section taken substantially on the line 6—6 of Fig. 1;

Fig. 7 is a view in perspective of the middle portion of any one of the revolvable shelves or trays adapted to be mounted upon the supporting standard and showing the

2

novel manner in which the crossed or latticed bars are secured to the flange of the standard encircling sleeve;

Fig. 8 is a sectional view taken substantially on the line 8—8 of Fig. 7; and

Fig. 9 is a sectional view taken at right angles to the section for Fig. 8 and substantially on the line 9—9 of Fig. 7.

Referring now more particularly to the drawings, the stand, in its preferred construction, embodies a base which

10 is generally designated 10 and a standard generally designated 12, supported upon the base in the manner about to be described. The standard 12 has mounted thereon a number of trays or shelves for rotary movement thereabout, whereby articles placed thereon may be readily 15 reached, and these trays or shelves may be of a number of different designs in the outer portions thereof but each is formed at its center in the same manner as the others, so as to give a strong and rugged construction with lightness of weight.

20 The details of the trays or shelves will be hereinafter particularly described.

The base 10 is preferably in the form of a large one piece circular body of inverted dished form and, therefore, has an upwardly bowed or arcuate top 14 defined 25 by the annular down-turned rim 16, the edge of which rests directly upon the floor or other support.

At the radial center of the top there is formed the opening 18 with which is aligned the upper end of a flanged sleeve 20, the flange 21 of which is positioned 30 against the underside of the top, as shown, and is secured thereto in a suitable manner, as by welding, as indicated at 22. This is the preferred construction but if desired the flange may be located on the upper side of the top and the sleeve extended through the opening.

35 Adjacent its lower end the sleeve has the diametrical openings 23 therethrough and the lower end of the standard 12, which is of tubular form, is extended into the sleeve 20 and is likewise provided with diametrical openings 24 which are brought into alignment with the openings 23, and a bolt 25 is passed through the aligned openings and provided with the usual nut 26 to secure it in place and thus rigidly secure the standard to the base.

40 The standard 12 may be formed in a single piece or as a single tube, but preferably it is formed in a number of sections, as illustrated, and three such sections are here shown which are designated 27, 28 and 29. The section 27 is the lowermost one and the section 28 is connected thereto by means of a pin 30 which is secured in the lower end of the section 28 and is of a diameter to 45 slip into the upper end of the section 27.

In the same manner the upper end of the middle section 28 is connected with the uppermost section 29 by a pin 31 one end of which is secured as by welding or the like, as shown in Fig. 5 at 32, in the lower end of the section 29 while the other end of the pin which projects from the section 29 is telescoped into the section 28. By 50 the formation of the standard 12 in a number of sections as shown, it will be seen that the stand may be given different heights by adding or subtracting these sections.

60 To facilitate the placement of the different trays on the standard at various elevations, the standard in its sections is provided with a multiplicity of relatively closely spaced diametrical openings 33 for the purpose hereinafter described.

65 In Fig. 1 there are shown two styles or forms of trays adapted to be mounted on the standard 12, one of which styles or forms is designated 34 while the other form is designated 35. However, all of the trays are alike with respect to the basic construction or central formation thereof as illustrated in particular in Figs. 7, 8 and 9. Accordingly this basic construction will be described as applying to any one of the trays and as is shown in the

figures referred to, there is provided a hub sleeve 36 of substantial length and of an inside diameter to snugly receive the standard 12. This sleeve 36 has its top end defined by the out-turned encircling flange 37.

The central part of each of the trays is in the form of a latticework which is generally designated 38 and which embodies the two relatively heavy, short parallel bars 39 which extend on opposite sides of the sleeve 36 against the underside of the flange 37 and the flange is bent down over the underlying bar 39 as indicated at 40, and is welded to the bars. Disposed at right angles to the two short bars 39 are two other short heavy bars 41 which are disposed on opposite sides of the sleeve and lie across and upon the top of the flange 37 and the portions of the flange adjacent to these bars 41 are bent or turned upwardly as indicated at 42 around undersides of the bars 41, as shown in Fig. 9.

The portions 40 and the portions 42 of the flange 37 may be welded to the adjacent bars and in addition the bars where they cross one another are also welded together as indicated at 43. Thus these four bars arranged in pairs which are in crossed or perpendicular relation, form a rigid latticework secured to the top end of the sleeve 36 to give a strong, lightweight construction and the latticework 38 forms the base or foundation for supporting other bars or other elements designed to carry merchandise for display. For example, in Fig. 1 and in Fig. 2 the tray or shelf structure is shown as embodying longer crossed or perpendicularly related bars 44 wherein two of these bars are in parallel relation and extend across and rest upon the outer ends of a pair of the lattice bars, as for example, the bars 39 to which they are spot welded, while the other two of the long bars 44 are arranged in spaced parallel relation and perpendicular to the first pair and lie across and are welded to the outer ends of the other pair of lattice bars 41. Thus in addition to the bars 44 being across and welded to the outer ends of the bars 39 and 41, they are also in crossed relation with one another and are welded together at the cross-over points 45.

The longer bars or arms 44 are here shown as having upturned outer end portions 46.

Obviously the form and number of the bars or arms 44 may be changed as may be required and in addition they may be employed or utilized to support other members in a manner to form a receptacle adapted to receive and carry smaller articles such as is shown in the form of the tray or shelf designated 34. In this construction a receptacle 47 is provided which embodies a central ring 48 which is secured by welding upon the uppermost pair of lattice bars 41 concentric with the sleeve 36. This ring has secured to it and radiating outwardly from it the spokes 49 which at their outer ends are turned up as indicated at 50 and the turned up ends are joined by a border ring 51. In addition to the ring 48 being welded or otherwise suitably fixed to the central lattice-work, a further rigidity can be given to the construction by welding the spokes 49 to the lattice-work bars and to the bars or arms 44 where the spokes cross the underlying bars.

The sleeve 36 of each of the trays is interiorly dimensioned, as previously stated, to snugly receive the standard 12 and the trays are maintained at desired elevations one above the other on the standard by the employment of pins 52 which are extended through the proper diametrical openings 33 beneath the tray sleeves 36 and the end of the pin may then be turned down as indicated at 53 to maintain it against accidental displacement, the other end of the pin being provided with a suitable head, as shown. Obviously with this means of supporting the trays on the standard the trays can be freely rotated about the standard while resting upon the supporting pins and if the size of the merchandise to be placed on the trays makes it necessary to separate the trays or give a wider spacing between them, the proper adjustment of the spacing can be effected by re-locating the pins 52.

The standard, as previously stated, is of tubular form and a suitable closure cap can be inserted into the top end thereof as indicated at 54.

In addition to supporting an auxiliary structure upon the latticework 38 or upon the arms 44, there is attached to one of the trays which would be used as the top tray of the series, a suitable sign or card supporting unit such as is shown in Figs. 1 and 4 and generally designated 55. This unit embodies a wide substantially U-shaped wire frame arranged in inverted position with the side members or legs 56 thereof looped around a pair of crossed lattice bars on opposite sides of the sleeve 36. For example, the loops designated 57, formed from the ends of the legs 56, may be closed one around a bar 41 at one side of the lattice structure or at one side of the sleeve 36, and the other around the opposite bar 41 at the opposite side of the lattice structure. Associated with the inverted U-shaped frame 56 is a substantially V-shaped wire frame 57 which is also in inverted position and placed against one side of the frame 56 with the free ends of the legs welded to the legs 56 adjacent to the loops 57. The V-frame as shown in Fig. 1, thus extends across the width of or straddles the frame 56 and also projects slightly above the part 58 which connects the legs 56 so that a display or price card can be slipped between the two frames, as will be readily apparent.

From the foregoing it will be seen that there is provided by the present invention a new and novel revolvable article support and display stand which can be built economically and which is relatively light in weight but at the same time, because of the novel way in which the elements are put together, will have considerable strength so as to support a multiplicity of heavy articles.

Also the parts are assembled in a novel manner so that they can be readily separated for packing and shipping and the structure can be easily and quickly set up without need for the employment of any special tools.

I claim:

1. A unit for use as a part of a display fixture embodying an upright standard; said unit comprising a sleeve adapted to have the standard extended therethrough, and a lattice structure comprising a plurality of bar members arranged to extend perpendicularly to the sleeve and fixed thereto outside of the area circumscribed by the interior cross section of the sleeve and each of said bar members crossing and being secured to at least two other bar members at the crossing points of such members, the lattice structure forming when the unit is mounted on a standard a substantially horizontal body supporting means, a receptacle supported upon the lattice structure and comprising an annulus concentric with and of only slightly larger diameter than said sleeve and resting upon and secured to said bars to form a fixed part of the unit, a multiplicity of bars in relatively closely spaced relation secured to and radiating from said annulus in a common plane therewith, said last mentioned bars having upturned outer end portions and a means joined to and connecting together said upturned outer end portions.

2. A tray unit for mounting upon a supporting standard; said unit comprising a tubular sleeve member having a top end joined to and defined by a surrounding flange and adapted to have the standard extended therethrough, and a lattice structure carried by said flange to lie in a plane perpendicular to the tube and comprising crossed rods at least two of which lie against and are fixedly joined to the underside of the flange and at least two others of which lie upon and are fixedly joined to the top of the flange, the first two rods and the said two others being rigidly joined together at their crossing points.

3. The invention according to claim 2, wherein the said flange has edge portions turned down over and partly around the rods lying against the underside and other

edge portions turned up and partly around the rods lying upon the top thereof.
